Primary Examiner — Paula Allen Greene(74) *Attorney, Agent, or Firm* — Maier & Maier, PLLC(57) **CLAIM**

The ornamental design for a speaker, as shown and described.

DESCRIPTION

FIG. 1 is a perspective view of a speaker, showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is cross-sectional view taken in the direction of line 8-8 of FIG. 2 and FIG. 4.

The broken lines illustrate portions of the speaker that form no part of the claimed design.
